CONVERSION OF HYDROCARBON OILS

Lyman C. Huff, Chicago, Ill., assignor to Universal Oil Products Company, Chicago, Ill., a corporation of Delaware

Application September 29, 1937, Serial No. 166,263

4 Claims. (Cl. 196—48)

This application is a continuation-in-part of my co-pending application filed on November 30, 1936, Serial No. 113,424, now Patent No. 2,177,829.

The invention relates to improvements in the type of process wherein hydrocarbon oils of different boiling range characteristics are separately cracked to produce high yields of good quality gasoline and minor yields of less valuable products comprising petroleum coke, light normally gaseous products and, when desired, heavy residual liquid suitable, for example, as fuel oil.

The process herein provided comprises two major and independently controlled but cooperative steps, the first of which is devoted to the separate pyrolytic conversion of selected relatively low-boiling and high-boiling fractions of the charging stock and intermediate liquid conversion products of the process, while the second is devoted to the coking of heavy residual liquid products produced in each of the two major steps, intermediate liquid products of the second step being returned to the fractionator and thence to the selective cracking stages of the first step, light distillate produced in the second step being also returned as a cooling and refluxing medium to the fractionator of the first step wherefrom it is recovered together with gasoline produced in the first step, the total gasoline product being stabilized to the desired vapor pressure and the gaseous products of the process being subjected to absorption to recover desirable high-boiling components therefrom. When desired, liquid residue may be recovered from either or both steps of the system. Charging stock for the process which may be any desired type of hydrocarbon oil but is preferably an oil of relatively wide boiling range, is preferably supplied as a cooling and refluxing medium to the fractionator of the second step of the system wherefrom it is subsequently supplied, together with the reflux condensate produced in the fractionator of said second step, to the fractionator of the first step.

The above outlined major features of the invention, as well as other features of a minor nature, are described more fully in conjunction with the following description of the accompanying drawing. The cooperative and interdependent nature of the various features of the invention and their advantages will be readily apparent to those familiar with the art by referring to the drawing and the following description thereof.

The drawing is diagrammatic and illustrates one specific form of apparatus in which the

process of the invention may be conducted to produce the desired results.

Referring to the drawing, an oil of relatively high-boiling characteristics is supplied, as will be later described, to heating coil 1 wherein it is heated to the desired cracking temperature, preferably at a substantial superatmospheric pressure by means of heat supplied from furnace 2, the heated products being discharged from coil 1 through line 3 and valve 4 into reaction chamber 5.

Simultaneously, an oil of relatively low-boiling characteristics is supplied, as will be later described, to heating coil 6 wherein it is heated preferably to a higher cracking temperature than that employed in heating coil 1. Heat is supplied to heating coil 6 from furnace 7. A substantial superatmospheric pressure is also preferably employed in heating coil 6 and the highly heated products are discharged therefrom through line 8 and valve 9 into reaction chamber 5.

Chamber 5 is also preferably maintained at a substantial superatmospheric pressure which may be substantially the same or somewhat lower than that employed in the communicating heating coil utilizing the lowest outlet pressure. Continued cracking of the heated products supplied to chamber 5 from coils 1 and 6 is accomplished therein and preferably the reaction chamber is insulated to conserve heat, although insulation is not shown in the drawing. In the particular case here illustrated, both vaporous and liquid conversion products are withdrawn in commingled state from the lower portion of chamber 5 and directed therefrom through line 10 and valve 11 into vaporizing and separating chamber 12. The products passing from chamber 5 to chamber 12 may be diluted and/or cooled by introducing any suitable diluent and/or cooling medium into line 10 on either or both sides of valve 11, lines 13 controlled by valves 14 being provided for this purpose, in the case here illustrated.

Chamber 12 is preferably maintained at a substantially reduced pressure relative to that employed in chamber 5. The reduction in pressure being accomplished as the heated products pass through valve 11 in line 10. This reduction in pressure also serves to partially cool the conversion products, prior to their introduction into chamber 12, and the heat liberated by the pressure reduction serves to effect further vaporization of the liquid products in chamber 12. Separation of the heavy liquid conversion products, which remain unvaporized in chamber 12, from

the lighter, vaporous components of the conversion products, is accomplished in this zone. The residual liquid is withdrawn from the lower portion of chamber 12 through line 15 and, when desired, may be removed in part, from the system to cooling and storage, or elsewhere, as a final residual liquid product of the process by means of line 16 and valve 17. However, at least a portion of the residual liquid is directed through valve 18 in line 15 to pump 19 by means of which it is fed through line 20 and may be directed through valve 21 in this line to further treatment, as will be later described, in heating coil 22, or it may be first supplied, all or in part, from line 20 through line 23 and valve 24 into separating chamber 25 wherefrom it is directed, together with other heavy liquid products from this zone, through line 26 and valve 27 to pump 28 and thence through line 29 and valve 30 to further treatment in heating coil 22.

Vaporous conversion products are removed from the upper portion of chamber 12 and directed through line 31 and valve 32 to fractionation in fractionator 33, wherein their components boiling above the range of the desired final gasoline product of the process are condensed as reflux condensate. The reflux condensate formed in fractionator 33 is separated therein into selected relatively low-boiling and higher boiling fractions. The latter are removed from the lower portion of the fractionator and are directed through line 34 and valve 35 to pump 36 by means of which they are supplied through line 37 and valve 38 to conversion, as previously described, in heating coil 1. The selected relatively low-boiling fractions of the reflux condensate formed in fractionator 33 may be removed from one or a plurality of suitable intermediate points in this zone and, in this case here illustrated, are directed through line 39 and valve 40 to pump 41 by means of which they are fed through line 42 and may be supplied, all or in part, through line 43 and valve 44 to conversion, as previously described, in heating coil 6.

Fractionated vapors of the desired end-boiling point are removed, together with normally gaseous products, from the upper portion of fractionator 33 and directed through line 45 and valve 46 to cooling and partial condensation in condenser 47, wherefrom the resulting distillate and the remaining uncondensed vapors and gases are directed through line 48 and valve 49 to collection in accumulator 50. Distillate thus collected in accumulator 50 may be recirculated in regulated quantities by means of line 51, valve 52, pump 53, line 54 and valve 55 to the upper portion of fractionator 33, to serve therein as a cooling and refluxing medium for assisting fractionation of the vapors and to maintain the desired vapor outlet temperature from the fractionator. The uncondensed vapors and gases are directed from accumulator 50 through line 56 and valve 57 to sub-cooler 58 wherein they are further cooled sufficiently to condense substantially all of their normally liquid components by circulating any suitable cooling medium through the sub-cooler by means of lines 59 and 61 controlled, respectively, by valves 60 and 62. The resulting distillate and uncondensed normally gaseous products are directed from sub-cooler 58 through line 63 and valve 64 to collection and separation in receiver 65. The uncondensed gases are withdrawn from receiver 65 through line 66 and, when desired, may be directed therefrom, all or in part, through line 67 and valve 68 to storage, or else-

where, as desired, or they may be passed through valve 69 in line 66 to absorption in absorber 70, the operation of which will be later described.

The high-boiling residual oil supplied to heating coil 22, as previously described, from chamber 25 and/or chamber 12, is heated in this zone preferably at a rapid rate to a sufficiently high temperature to induce subsequent reduction of its high-boiling components to substantially dry coke in coking chamber 100. Furnace 80 supplies the required heat to the oil passing through heating coil 22 and the highly heated residual liquid is discharged therefrom through line 95, wherefrom it is directed into coking chamber 100 at any desired point or plurality of points in this zone; lines 96 and 98 controlled, respectively, by valves 97 and 99 being shown in the drawing for the introduction of heated residual oil into the upper and lower portions, respectively, of the reaction chamber.

The coke formed in chamber 100 is allowed to accumulate therein and may be removed from this zone by any well known means, not illustrated, after the chamber is substantially filled or after its operation has been completed, for any other reason. Preferably, a plurality of coking chambers is provided, although only a single coking chamber is illustrated in the drawing, and, preferably, the various chambers are alternately operated, cleaned and prepared for further operation in order that the coking stage, in common with the rest of the system, may be operated continuously. Chamber 100 is provided with a suitable drain line 101 controlled by valve 102 and this line may also serve, when desired, as a means of introducing water, steam, or any other suitable cooling medium into the chamber, after its operation has been completed and preferably after it has been isolated from the rest of the system, in order to hasten cooling and facilitate removal of the coke.

The vapors evolved from the residue undergoing coking in chamber 100 will normally contain a substantial quantity of entrained and/or dissolved heavy liquids unsuitable for further cracking in heating coils 1 or 6. These vaporous products are therefore directed from chamber 100 through line 103 and valve 104 into separating chamber 25 wherein they are partially cooled and washed to effect the removal therefrom of said undesirable high-boiling components. The latter are removed from the lower portion of chamber 25, either alone or together with the non-vaporous components of any residual liquid supplied to this zone, as previously described, from chamber 12, and are directed through line 26 and valve 27 to pump 28 wherefrom they are fed through line 29 and may be supplied through valve 30 in this line directly to heating coil 22 or they may be diverted from line 29 through line 105 and valve 106 into chamber 12, in which case, residual liquid from the latter zone is supplied directly, as previously described, to heating coil 22. When desired a regulated quantity of the heavy liquid products withdrawn from the lower portion of chamber 25 may be removed from the system to cooling and storage or elsewhere, as desired, as a final residual liquid product of the process by means of line 107 and valve 108.

Relatively clean components of the vaporous products supplied to and evolved in chamber 25, which remain uncondensed in this zone, are directed therefrom through a suitable partition or

tray 109, which separates chamber 25 from fractionator 110, into the latter zone.

The high-boiling components of the vaporous products supplied, as described, to fractionator 110, are condensed in this zone as reflux condensate and, in order to assist fractional condensation of the vapors, charging stock of the process is preferably directly commingled with the vaporous products undergoing fractionation

- 10 in fractionator 110. In the case here illustrated, the charging stock is supplied from any suitable source through line 111 and valve 112 to pump 113 by means of which it is fed through line 114 and may be introduced into fractionator 110 at 15 any desired point or plurality of points in this zone by means of branch lines 115 controlled by valves 116. The high-boiling fractions condensed as reflux condensate from the vapors in fractionator 110 as well as any high-boiling components of the charging stock, which remain unvaporized in fractionator 110, are directed from the lower portion of this zone through line 117 and valve 118 to pump 119 by means of which these commingled oils are supplied through line 25 120 to fractionator 33, entering the latter zone at any desired point or plurality of points therein by means of branch lines 121 controlled by valves 122. The commingled charging stock and reflux condensate thus supplied from fractionator 30 110 to fractionator 33, is separated in the latter zone into selected relatively low-boiling and higher boiling fractions which are supplied, respectively, to conversion in heating coils 6 and 1, together with the corresponding relatively low-boiling and high-boiling fractions of the reflux condensate formed, as previously described, in fractionator 33.

In the particular case here illustrated, in order to partially cool the vaporous products in chamber 25 and effect the separation of undesired heavy liquid components therefrom, a relatively low-boiling fraction of materials condensed in fractionator 110 is withdrawn as a sidestream from the upper portion of this zone and directed through line 123 and valve 124 to pump 125 by means of which it is introduced in regulated quantities through line 126 and valve 127 into the upper portion of chamber 25, preferably being sprayed or otherwise intimately contacted with 45 the vapors in this zone by means, for example, of a suitable spreader flange or spray arrangement 128.

Low-boiling components of the materials supplied to fractionator 110, which remain uncon- 50 densed in this zone, are directed in vaporous state from the upper portion thereof through line 130 and valve 131 to condensation and cooling in condenser 132. The resulting distillate and uncondensed gases are directed through line 133 55 and valve 134 to collection and separation in receiver 135. The uncondensed gases are withdrawn from receiver 135 through line 136 and may be directed therefrom, all or in part, when desired, through line 137 and valve 138 to storage 60 or elsewhere, as desired, or they may be directed through valve 139 in line 136 and through line 140 to absorber 70. The distillate collected in receiver 135 is directed therefrom through line 141 and valve 142 to pump 143 by means of which 65 it is fed through line 144, and regulated quantities of this material may be diverted from line 144 through line 145 and valve 146 into the upper portion of fractionator 110 to serve as a cooling and refluxing medium in this zone, while 70 75 the remaining portion of the distillate is directed

through valve 147 in line 144 into fractionator 33, wherein it serves as a cooling and refluxing medium and wherein the components thereof boiling within the range of the desired final gasoline product of the process are revaporized and directed, together with the gasoline formed in this stage of the system, through line 45 and valve 46 to the subsequent treatment previously described.

The distillate collected in receiver 65 which 10 comprises the total net gasoline production of the system, is withdrawn therefrom through line 150 and valve 151 to pump 152 by means of which it is supplied through line 153, valve 154, heat exchanger 155, line 156 and valve 157 to stabilizer 158. The purpose of heat exchanger 155 is to 15 reheat the distillate sufficiently to effect partial vaporization thereof and, in the particular case here illustrated, this heat is recovered from within the system, as will be later described.

Regulated quantities of dissolved gases are liberated from the distillate in stabilizer 158, whereby to reduce its vapor pressure to the desired degree. To assist in establishing equilibrium conditions in the stabilizer, cooling is provided in 25 the upper portion thereof, as will be later described, and the distillate collected in the lower portion of the stabilizer is reboiled. The reboiling is accomplished, in the case here illustrated, by directing the distillate from the lower portion 30 of the stabilizer through line 159 and valve 160 to a suitable heat exchanger or reboiling drum 170, wherein heat for reboiling is supplied to the distillate by circulating regulated quantities of the light reflux condensate formed in fractionator 33 in indirect heat exchange therewith, as will be later described. The vapors and gases evolved in reboiler 170 are returned therefrom through line 171 and valve 172 to stabilizer 158. The stabilized and reboiled distillate is withdrawn 40 from the lower portion of reboiler 170 and, in the case here illustrated, is directed through line 173 and valve 174 to and through heat exchanger 155, wherein it supplies heat to the distillate passing through this zone to stabilizer 158, as previously described, and wherefrom the resulting partially cooled distillate is directed through line 175 and valve 176 to further cooling and storage or to any desired further treatment, not illustrated.

Light reflux condensate for effecting reboiling of the distillate in reboiler 170 is supplied thereto from pump 41 and line 42 through line 177 and valve 178. The resulting partially cooled light reflux condensate is discharged from reboiler 170 55 through line 179 and, in the particular case here illustrated, is directed through valve 180 in this line into the upper portion of vaporizing and separating chamber 12, wherein it serves as a cooling and refluxing medium for assisting the 60 desired separation of vaporous and residual liquid products in this zone.

The gases liberated from the distillate and remaining uncondensed in the stabilizer 158 are directed from the upper portion thereof through 65 line 181 and valve 182 to condenser 183 wherein these materials are cooled sufficiently to effect partial condensation thereof by passing the same in indirect heat exchange with any suitable cooling medium, which is circulated through condenser 183, by means of lines 184 and 186 controlled, respectively, by valves 185 and 187. The 70 condensed components of the products released from the upper portion of stabilizer 158 are directed from condenser 183 through line 188 and 75

valve 189 to collection and separation in accumulator 190. The condensate is recirculated in regulated quantities, by means of line 191, valve 192, pump 193, line 194 and valve 195, to the upper portion of stabilizer 158 wherein it serves as a cooling and refluxing medium. The uncondensed gases collected in accumulator 190 are directed therefrom through line 196, valve 197 and line 140 to absorber 70.

10 The gaseous products supplied, as described, to absorber 70 contain a substantial quantity of high-boiling components such as butane, butenes and a portion of the propane and propene, a high proportion of which high-boiling gases may 15 be concentrated in the final gasoline product without excessively increasing its vapor pressure.

The purpose of absorber 70 and stabilizer 158 and their appurtenances herein provided is to 20 separate substantially all of the low-boiling gases from the final gasoline product of the process and concentrate therein substantially only the relatively high-boiling normally gaseous products. This is accomplished by absorbing the desirable high-boiling components from the gases in absorber 25 70 in an absorber oil comprising selected relatively low-boiling fractions of the intermediate liquid conversion products of the process, returning the enriched absorber oil to fractionator 33 to increase the concentration of high-boiling 30 gases in the overhead vaporous stream from this zone and thereby increase the concentration thereof in the distillate collected in receiver 65, stabilizing the distillate to the desired vapor pressure and returning the gases liberated from the 35 distillate by said stabilization to absorber 70.

The absorber oil utilized, in the particular case illustrated, is a regulated quantity of the low-boiling reflux condensate recovered from fractionator 33. This material is diverted from line 40 42 through line 209 and valve 201 to heat exchanger 203 wherein it is partially cocled, as will be later described, and wherefrom it is directed through line 204 and valve 205 to further cooling in cooler 206, through which any suitable cooling 45 medium is passed by means of lines 207 and 209 controlled, respectively, by valves 208 and 210.

The resulting cool absorber oil is directed from cooler 206 through line 211 and valve 212 into the upper portion of absorber 70, wherein it passes 50 in direct counter-current contact with the ascending gases in this zone and absorbs desirable high-boiling components therefrom. The low-boiling gaseous products which remain unabsorbed in absorber 70 are released from the upper portion 55 of this zone through line 213 and valve 214 to storage or elsewhere, as desired. The enriched absorber oil is withdrawn from the lower portion of absorber 70 through line 215 and valve 216 to pump 217 by means of which it is fed through 60 line 218 and valve 219 to heat exchanger 203, wherein it is heated by indirect heat exchange with the light reflux condensate supplied to this zone, as previously described, and wherefrom the resulting enriched hot absorber oil is directed 65 through line 220 and valve 221 into fractionator 33.

The preferred conditions of operation which 70 may be employed, in an apparatus such as illustrated and above described, to produce the desired results, may be as follows: A temperature of the order of 850 to 950° F. and a superatmospheric pressure of from 100 to 350 pounds, or more, per square inch, is preferably employed at the outlet of heavy oil heating coil 1. Light oil heating coil 6 preferably employs a higher tem-

perature which may range, as measured at the outlet, from 900 to 1000° F., or thereabouts, preferably with a superatmospheric pressure at this point in the system of from 200 to 500 pounds, or more, per square inch. The reaction chamber 5 is also maintained at an active cracking temperature and at a substantial superatmospheric pressure which may be approximately the same or somewhat lower than that employed in the communicating heating coil utilizing the lowest 10 pressure. Vaporizing and separating chamber 12 preferably employs a substantially reduced pressure relative to that utilized in the reaction chamber, the reduced pressure ranging, for example, from 100 pounds, or thereabouts, per square inch, 15 superatmospheric, down to substantially atmospheric pressure, the preferred pressure in this zone being of the order of 25 to 75 pounds per square inch, superatmospheric. Fractionator 33 and the succeeding condensing and collecting 20 equipment may be operated at any desired pressure from substantially atmospheric up to substantially the same pressure as that employed in vaporizing and separating chamber 12. Heating coil 22 of the coking stage of the system, in 25 which high rates of heating and a high oil velocity are preferably employed, may utilize an outlet temperature ranging, for example, from 850 to 1000° F. and a superatmospheric pressure of from 30 25 to 200 pounds, or more, per square inch, the preferred conditions at the outlet of heating coil 22 being 900 to 950° F. and 50 to 150 pounds per square inch, or thereabouts, superatmospheric pressure. The coking chamber may employ any 35 desired pressure ranging from substantially atmospheric up to approximately the same as that employed at the outlet of heating coil 22. The separating and fractionating column to which vaporous products of the coking operation are supplied and the succeeding condensing and collecting equipment may employ pressures ranging from substantially atmospheric up to substantially the same pressure as that employed in the coking chamber. Absorber 70 is preferably operated at a superatmospheric pressure of from 50 to 175 pounds, or more, per square inch and a superatmospheric pressure of the order of 50 to 250 pounds, or thereabouts, per square inch, is 45 preferred in stabilizer 158.

As an example of one specific operation of the 50 process, as it may be conducted in an apparatus such as illustrated and above described: The charging stock is a Bahrein Island reduced crude of approximately 17.5° A. P. I. gravity which contains approximately 6% of fractions boiling up 55 to 572° F., approximately 50% at 698° F., with an end-boiling point of approximately 750° F. and containing approximately 10% of coke by weight. In this operation, the temperature employed at the outlet of heavy oil heating coil 1 is approximately 915° F., with a superatmospheric pressure at this point in the system of approximately 200 pounds per square inch. Light oil heating coil 6 employs an outlet conversion temperature of approximately 955° F. and a superatmospheric 60 pressure of approximately 260 pounds per square inch. The reaction chamber is operated at a superatmospheric pressure of approximately 200 pounds per square inch, which is reduced in the succeeding vaporizing and separating chamber 70 to approximately 75 pounds per square inch, superatmospheric. Approximately the same pressure is employed in the succeeding condensing and collecting equipment of this stage of the system. Residue heating coil 22 employs an outlet 75

temperature of approximately 950° F. and the pressure employed in this zone, as measured at the outlet thereof, is approximately 100 pounds per square inch, superatmospheric. The coking chamber is operated at a superatmospheric pressure of approximately 50 pounds per square inch and this pressure is substantially equalized in the succeeding separating, fractionating, condensing and collecting equipment.

10 In the above operation, the charging stock is supplied to the fractionating column of the coking stage of the system and reflux condensate from this zone is returned to fractionator 33, as is also distillate resulting from condensation of the overhead vaporous stream from the fractionator of the coking stage. Residual liquid from vaporizing and separating chamber 12 is supplied to separating chamber 25 of the coking stage of the system and non-vaporous residual liquid from the latter zone is supplied to heating coil 22 of the coking stage. A portion of the light reflux condensate from fractionator 33 is utilized as absorber oil in absorber 70 and the resulting enriched absorber oil is returned to fractionator 33.

This operation will yield per barrel of charging stock approximately 60% of 400° F. end-point gasoline having an octane number of approximately 68, as determined by the motor method. 30 The only other products of this operation are relatively light gases and about 88 pounds of low volatile coke per barrel of charging stock.

I claim as my invention:

1. A conversion process which comprises subjecting hydrocarbon oil to cracking conditions in a cracking zone and separating the resultant products into vapors and unvaporized oil in a separating chamber, removing unvaporized oil from said chamber and reducing the same to coke in a coking zone, introducing the vaporous products from the coking zone into a second separating chamber and therein separating high-boiling components of these products, then fractionating the remainder of said vaporous products independently of the first-mentioned vapors to separate therefrom a relatively heavy reflux condensate and a lighter reflux condensate, introducing the latter into contact with the vaporous products in said second chamber to assist the separation of said high-boiling components, introducing the first-mentioned vapors and said heavy reflux condensate into a fractionating zone and therein fractionating the former in contact with the latter, supplying reflux condensate from the fractionating zone to said cracking zone, and finally condensing the fractionated vapors.

2. A conversion process which comprises subjecting hydrocarbon oil to cracking conditions in a cracking zone and separating the resultant products into vapors and unvaporized oil in a separating chamber, removing unvaporized oil from said chamber and reducing the same to coke in a coking zone, introducing the vaporous products from the coking zone into a second separating chamber and therein separating high-boiling components of these products, then fractionating the remainder of said vaporous products independently of the first-mentioned vapors to separate therefrom a relatively heavy reflux condensate and a lighter reflux condensate, introducing the latter into contact with the vaporous products in said second chamber to assist the separation of said high-boiling components, introducing the first-mentioned vapors and said

heavy reflux condensate into a fractionating zone and therein fractionating the former in contact with the latter, separating from the contacting vapors and condensate in the fractionating zone relatively heavy and light cracking stocks, supplying the heavier cracking stock to said cracking zone, subjecting the lighter cracking stock to independently controlled cracking conditions and introducing resultant products to the first-mentioned separating chamber, and finally condensing the fractionated vapors.

3. In a process wherein vaporous and liquid products resulting from the pyrolytic conversion of hydrocarbon oils are supplied in commingled state from an enlarged reaction chamber maintained at substantial super-atmospheric pressure to a reduced pressure vaporizing and separating chamber wherein said liquids are appreciably further vaporized and wherefrom the vapors and resultant liquid residue are separately removed, the vapors fractionated to form reflux condensate which is returned to said pyrolytic conversion and a distillate boiling within the range of gasoline recovered from the fractionated vapors, the improvement which comprises introducing residual liquid removed from said vaporizing and separating chamber into a coking chamber wherein its high-boiling components are reduced to coke, supplying vaporous products of the coking operation to another separating chamber wherein high-boiling components, comprising entrained heavy liquids, are removed therefrom, removing said high-boiling components as residual liquid from said separating chamber, reducing their heavy components to coke in said coking chamber, independently fractionating the remaining relatively clean components of the vaporous products of the coking operation in contact with charging oil for the process to form a mixture of unvaporized charging oil and reflux condensate, supplying this mixture to the first-mentioned fractionating step and then to said pyrolytic conversion, together with the first-named reflux condensate and recovering from the lower-boiling components of said relatively clean vapors additional fractions boiling within the range of gasoline, and introducing into contact with the vapors in the second-mentioned separating chamber a light reflux condensate from said independent fractionating step.

4. A conversion process which comprises subjecting hydrocarbon oil to cracking conditions in a cracking zone and separating the resultant products into vapors and unvaporized oil in a separating chamber, removing unvaporized oil from said chamber and reducing the same to coke in a coking zone, introducing the vaporous products from the coking zone into a second separating chamber and therein separating high-boiling components of these products, then fractionating the remainder of said vaporous products to separate therefrom a relatively heavy reflux condensate and a lighter reflux condensate, introducing the latter into contact with the vaporous products in said second chamber to assist the separation of said high-boiling components, independently fractionating the first-mentioned vapors and combining reflux condensate thus formed with at least a portion of said heavy reflux condensate, supplying the resultant mixture to said cracking zone, and finally condensing the fractionated vapors.

LYMAN C. HUFF.
